UNITED STATES PATENT OFFICE

163,547

CANDELABRUM

Clifford D. Stewart, Boston, Mass.

Application January 4, 1950, Serial No. 7,001

Term of patent 7 years

(Cl. D48—2)

To all whom it may concern:

Be it known that I, Clifford D. Stewart, a citizen of the United States of America, residing at Boston, in the county of Suffolk and Commonwealth of Massachusetts, have invented a new, original, and ornamental Design for Candelabrum, of which the following is a specification, reference being had to the accompanying drawings, forming part thereof.

Fig. 1 is a side elevational view of a candelabrum, showing my new design;

Fig. 2 is a top plan view thereof; and

Fig. 3 is a perspective view.

The dotted lines shown in the drawing are for illustrative purposes only.

I claim:

The ornamental design for a candelabrum, substantially as shown and described.

CLIFFORD D. STEWART.
